UNITED STATES PATENT OFFICE.

JOHN NORMAN ANDERSON, OF METHUEN, MASSACHUSETTS.

BOBBIN.

Application filed November 17, 1925. Serial No. 69,612.

The present invention relates to an improvement in bobbins.

The object of the invention is to improve the construction of bobbins to render them more durable and satisfactory in use. To the above ends, the present invention consists in the bobbin hereinafter described and particularly defined in the claims.

In the accompanying drawings illustrating the preferred form of the invention, Fig. 1 is a longitudinal, sectional elevation of the bobbin; and Fig. 2 is a detail hereinafter referred to.

The illustrated embodiment of the invention is described as follows: The body of the bobbin 1 is provided with a blade 2 and a butt 3. The butt of the bobbin has an enlarged end. It receives the reinforcing rings 4, sprung into grooves formed in the exterior surface of the butt of the bobbin. These reinforcing rings 4 serve not only as devices to strengthen the butt of the bobbin, and to prevent splitting, but they also serve as the holding means by which the bobbin 25 is held in the shuttle of a weft replenishing loom.

The butt of the bobbin is provided with a concentric recess or spindle hole which is reinforced with a ferrule 5, shown in side elevation in Fig. 2. This ferrule is cylindrical in form throughout the principal portion of its length, and fits inside the butt recess 6 of the bobbin. Near the inner end of the body of the ferrule it is provided with an expanded portion or rounded or filleted enlargement 7, which, as shown, is located close to but short of the end of the ferrule. The bobbin butt is provided with an annular recess 8, which is located at such a distance from the end of the bobbin as to be adapted to receive the enlargement 7 of the ferrule when the latter is forced into the hole in the end of the bobbin. It is to be observed that the enlargement 7 is intermediate the ends of the body of the ferrule, and that in inserting the ferrule in the bobbin this enlargement of the ferrule is pressed into a hole in the wood somewhat smaller than the size of the enlargement.

The wood of the bobbin at the time it is receiving this ferrule is in such a condition that it will withstand the compression incident to the passage of the enlargement by it, and will more or less close in on the body of the ferrule after the enlargement has passed. This enlargement is received in the

annular recess 8, and variations from accurate positioning of the recess 8 in the bobbin with respect to the enlargement on the ferrule may occur without impairing substantially the holding quality of the enlargement by engagement with the recess. This is a feature of importance, as it eliminates the necessity for the utmost precision in the manufacture of the bobbin blanks. This ferrule body maintains the correct size of the inside of the bobbin butt so that bobbins subjected to repeated handling will still retain a uniform diameter of hole so that they will position themselves correctly on the spindle of the spinning frame.

The outer end of the ferrule body is provided with a flange 9, which extends outwardly and then bends back parallel to the body of the ferrule at a distance therefrom. This concentric circular inturned edge of the ferrule flange, as it may be called, is provided with teeth or irregularities, which, when the ferrule is inserted in the bobbin, indent themselves into the end of the body of the bobbin, so as to secure a firm hold on the wood of the bobbin by the deformation thereof and acting thereby to prevent the ferrule from rotating in the shuttle body.

The ferrules are made of the form shown in Fig. 2. The bobbins are made of the form shown in Fig. 1, with the annular recess 8 formed therein, but without any recess to receive the back-turned, or inturned serrated edge of the ferrule flange which, under the pressure exerted in forcing the ferrule into the bobbin, indents itself into the end of the bobbin.

The forcing of the enlargement of the ferrule body through the smaller opening in the end of the bobbin butt subjects the wood to a strain which, in some instances, would be sufficient to crack it, but in the manufacture of bobbins of this construction, the bobbin is embraced and tightly held by a gripping device so as to prevent any expansion of the bobbin butt by the pressure exerted on the inside thereof by the enlargement on the body of the ferrule.

While the present invention is illustrated as embodied in a bobbin for use in a weft replenishing loom, it is to be understood that the invention may be employed in any form of bobbin provided with a central opening which it is desired to reinforce, or in the manufacture of spools, or other things having a central opening which is reinforced;

the claims, therefore, are to be read and understood in the light of this statement, as embracing any article of manufacture made of soft material such as wood, which is provided with a hole and reinforced by a ferrule having the features of construction defined in the claims.

Having thus described the invention, what is claimed is:

10. 1. A bobbin for weft replenishing looms having a wooden body portion consisting of a blade and an enlarged butt provided with a concentric spindle hole, reinforcing rings on the exterior of the butt of the bobbin, and a reinforcing ferrule on the interior of the butt of the bobbin, provided with an annular filleted enlargement near but short of its inner end, the hole in said bobbin butt being provided with a recess to receive 20 said enlargement, and said ferrule being also provided with an outwardly extended flange having a backwardly extended, irregularly formed edge adapted to penetrate the end of the bobbin and hold the ferrule from 25 rotation with respect thereto by deformation of the wood by the backwardly extended edge.
2. A bobbin having a butt of compara-

tively soft material, provided with a hole in its end, an outwardly flanged reinforcing metallic ferrule provided intermediate its ends with an annular filleted enlargement on its body, said hole in the bobbin being provided with an annular recess to receive such enlargement, and cooperating projections and recesses on the bobbin and ferrule to hold the ferrule from rotation with respect to the bobbin.

3. A bobbin having a body portion of comparatively yielding material, having an exterior strengthening reinforcement, and an interior strengthening reinforcement, consisting of a ferrule having an enlargement on the body thereof, said hole in the article being provided with an annular recess to receive the enlargement on the body of the ferrule, said ferrule being provided with an outwardly extended flange having a backwardly turned concentric circular lip adapted to be forced into the end of the body of the article to hold the ferrule and article from rotation with respect to each other.

In testimony whereof I have signed my name to this specification.

JOHN NORMAN ANDERSON.
